UNITED STATES PATENT OFFICE.

JOHN A. DE LON, OF RUSSIAVILLE, INDIANA.

GAME APPARATUS.

SPECIFICATION forming part of Letters Patent No. 718,986, dated January 27, 1903.

Application filed May 16, 1902. Serial No. 107,669. (No model.)

To all whom it may concern:

Be it known that I, JOHN A. DE LON, a citizen of the United States, residing at Russiaville, in the county of Howard and State of Indiana, have invented a new and useful Game Apparatus, of which the following is a specification.

This invention relates to certain improvements in game apparatus of that class in which a revoluble dial or hand is set into motion by the use of the train of clockwork, and has for its principal object to provide an improved form of the machine in which the dial or pointer is rotated at different speeds through different periods of time at successive operations, the player being unable to determine in advance the exact length of time of rotation of the dial, its stopping-point being merely a matter of chance.

20 A further object of the invention is to provide a simple form of mechanism for releasing the clockwork, such mechanism being operable only on the insertion of a ball, coin, or other object of predetermined size.

25 With these and other objects in view the invention consists in the novel construction and arrangement of parts hereinafter described, illustrated in the accompanying drawings, and particularly pointed out in the appended claims.

30 In the drawings, Figure 1 is a perspective view of a game apparatus constructed in accordance with my invention. Fig. 2 is a transverse sectional elevation of the same. Fig. 3 is a longitudinal sectional elevation of the apparatus on the line 3 3 of Fig. 2. Fig. 4 is a face view illustrating a modified construction of the apparatus. Fig. 5 is a view of a detail of construction.

40 Similar numerals of reference are employed to indicate corresponding parts throughout the several figures of the drawings.

10 designates a suitable casing having a circular opening or transparent panel 11 immediately in front of the revoluble dial or pointer. Within the casing is mounted a frame carrying a train of gearing comprising a spring 12, mounted on a winding-post 13, and the several gears 14, 15, 16, 17, 18, and 19, the arbor of the gear 19 carrying a fly 20. On the arbor 21 is secured a snail 22 for imparting movement to the locking-arm 23, the

latter being adapted to engage with notches in a locking-wheel 24 of a construction somewhat similar to that employed in the ordinary striking-train of a clockwork mechanism, but the notches being arranged in arbitrary order, so that the player on starting the mechanism into operation cannot determine in advance the exact length of time which the machine will operate. The locking-arm is mounted on a rock-shaft 25, provided with a trip-arm 26, the lower end of which is in alignment with a plunger 27, extending through a guiding-tube 28, the outer end of the plunger 65 being provided with a push-knob 29 at a point outside the casing and being normally held in inoperative position by a spring 30. The inner end of the tube 28 extends beyond the inner end of the plunger and forms a seat 70 or support for the reception of a ball, coin, or other object *x*, which is dropped into the machine through a chute 31. The ball or other object is received on the projecting end of the tube 28 at a point between the inner end 75 of the plunger and the trip-arm 26, so that when the plunger is pushed inwardly against the action of the spring 30 the trip-arm 26 will be forced back, raising the locking-arm 23 from the notch in which it may happen to rest 80 and permitting the movement of the train of gearing. The ball, coin, or other object when pushed beyond the end of the tube 28 falls through a tube 32 to a receiving-drawer 33.

On the front end of the arbor or spindle 34 85 is secured an arm 36, carrying a pawl 37, which is normally held by a spring 38 in engagement with the teeth of a ratchet-wheel 39, carried by a revoluble dial 40. The dial 40 is mounted loosely on the spindle 34, and 90 on its face are arranged one or more rows of spaces bearing designating-marks, such as numerals or appropriate phrases or the like. In the present instance the dial is provided with numerals, the highest of which is "25," 95 so that the apparatus may be employed in playing pachisi or other games where the numbers gained by the players is a matter of chance. The construction is such that the disk carrying the numerals or other designated data will be rotated through the engagement of the pawl 37 with the ratchet-wheel 39, the extent of movement being governed by the distance between the notches of

the locking-disk. The momentum acquired by the disk is then sufficient to keep it revolving for a considerable period of time and when finally stopped the spring-pointer 41 designates the number gained by the player. For convenience the pointer 21 is arranged to make contact with a series of pins 42, projecting from the face of the dial, so that there can be no question as to the exact stopping-point of the dial.

In Fig. 4 I have illustrated a slight modification of the invention, the dial in this case being stationary and a hand or pointer 40' being mounted on the spindle 34 in the same manner as the dial 40 is mounted on the spindle of the apparatus as shown in Figs. 2 and 5.

The apparatus may be employed for playing games of any kind where numbers, phrases, or other characters determine the position of the player or playing-pieces or may be employed as a fortune-telling wheel or for similar purposes.

While the construction herein described, and illustrated in the accompanying drawings, is the preferred form of the device, it is obvious that various changes in the form, proportions, size, and minor details of the structure may be made without departing from the spirit or sacrificing any of the advantages of the invention.

Having thus described my invention, what I claim is—

1. In a device of the class specified, the combination with a revolute member, of a clockwork mechanism connected to said revolute member and having as one of its ele-

ments a locking-wheel provided with locking-notches spaced at irregular intervals, a locking-arm adapted to engage in said notches, a trip-arm connected to said locking-arm, a plunger, and a chute for delivering an object between the end of the plunger and the trip-arm.

2. In a device of the class specified, the combination of the casing, a clockwork mechanism mounted therein and including a locking-wheel having a series of locking-notches disposed at irregular intervals, a rock-shaft, a locking-arm carried thereby and adapted to engage in the notches, a snail for elevating said arm at regular intervals when the clockwork mechanism is released, a tube 28 having at one end a seat for the reception of a ball, a plunger guided in said tube and extending outside the casing, a push-knob on 55 said plunger, a compression-spring extending between the push-knob and casing, a ball guiding and delivering chute terminating at a point above the ball-seat, a trip-arm secured to the rock-shaft and locking-arm and 60 having its lower end arranged in the path of movement of the ball and plunger, and a guiding-chute for receiving and delivering the ball after the same has been forced from its seat by the plunger.

In testimony that I claim the foregoing as my own I have hereto affixed my signature in the presence of two witnesses.

JOHN A. DE LON.
